 M. H. Rhodes, Inc., New York, N. Y., a corpora-
 tion of Delaware

Application March 20, 1937, Serial No. 132,019

8 Claims. (Cl. 200—39)

This invention relates to electric switches, and with regard to certain more specific features, to electric time-controlled switches.

The present invention is in the nature of an improvement on the invention shown and claimed in my copending application Serial No. 673,421, filed May 29, 1933, now Patent No. 2,087,071 dated July 13, 1937.

Among the several objects of the invention may be noted the provision of an electric switch of the class described having a plurality of circuit making and breaking positions, part of said positions being time-controlled, and part being independent of time control; the provision of an electric switch of the class described which is particularly adapted for the operation of electrical resistance heating units, such as used in electrical stoves, so that a timed period of high heat may be had, after which a period of relatively lower heat will commence and continue until a manual turning "off" operation is carried out; the provision of an electric time-controlled switch of the class described which has but one handle for both actuating and setting purposes for all circuit connections, said handle being arranged to be used consecutively as a switch-actuating handle and then as a time setting handle; and the provision of a switch of the class described which is relatively simple in construction and operation, and which is so constructed as to have a minimum number of wearing parts. Other objects will be in part obvious and in part pointed out hereinafter.

The invention accordingly comprises the elements and combination of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a front elevation of a time-controlled switch embodying the present invention;

Fig. 2 is a back elevation of the switch shown in Fig. 1;

Fig. 3 is a plan view of a base forming a part of the switch of Fig. 1, and is also a cross section taken along line 3—3 of Fig. 4;

Fig. 4 is a cross section taken substantially along line 4—4 of Fig. 3;

Figure 5, 6, and 7 are views similar to Fig. 3 showing alternative positions of certain elements;

Fig. 8 is a fragmentary cross section taken substantially along line 8—8 of Fig. 6;

Fig. 9 is a horizontal cross section taken substantially along line 9—9 of Fig. 4; and, Fig. 10 is a perspective view of a latch lever.

Similar reference characters indicate corresponding parts throughout the several views of the drawings.

In my aforesaid copending patent application, I have shown a form of electric time-controlled switch which is of great advantage in that it has but a single operating handle for controlling both the turning "off" and "on" of the switch, and for setting the time interval for which the switch is to automatically operate. It is a primary purpose of the present invention to retain this structural characteristic of a single handle, but to additionally incorporate within the switch structure an electrical switch, operable from the same handle, but controlling another set of circuit conditions. This additional switch, in the present invention, is a non-time-controlled switch, consequently it is operated only by its manual actuation of the single handle heretofore referred to. At the same time, said handle is available for all of the purposes found in my aforesaid copending application.

Referring now more particularly to Fig. 1, it will be seen that the switch of the present invention is enclosed in a housing indicated generally by numeral 1. Rotatably mounted at the center of the upper face of the housing 1 is a knob 3. This knob 3 is mounted on the end of a main shaft 5 (see Fig. 4) hereinafter to be described in greater detail. A projection 7 molded in the housing 1 serves as a stop to prevent the rotation of the knob 3 in the wrong direction. The upper face of the casing 1 contains index characters positioned to cooperate with the knob 3, said index characters being circularly arranged about the face of the casing and comprising an "off" position 9, a "low" position 11, and a numbered, graduated scale 13. The numbers of the scale 13 indicate the particular delay for which the switch is set at any given instant. A dot or other suitable indicating mark 15 is also provided on the face of casing 1, for purposes to be explained hereinafter.

The rear face or base 17 of the casing 1, as shown in Fig. 2, mounts the terminals of the switches of the present invention, which comprise three binding posts 19, 21, and 23. The character of the switching elements within the switch, hereinafter to be described, are such that when the knob 3 points to the "off" position 9, none of the terminals 19, 21, and 23 are connected together; when the knob 3 points to the "low" 55

position 11, connections are made inside the switch between terminals 19 and 21 but not between terminals 21 and 23; but when the knob 3 is in suitably actuated position anywhere on the scale 13, connections are not only made between terminals 19 and 21, but also between terminals 21 and 23, with an automatic time delay device running to disconnect the terminals 21 and 23 after the expiration of a predetermined time interval.

From this brief description of the function of the switch, its utility in a circuit connection such as for the heating elements of an electric stove can be seen. Diagrammatic circuit connections are indicated in Fig. 2 for this purpose. For example, index characters 25 and 27 indicate a pair of power wires. The wire 27 is connected to the terminal 21. Terminal 19 is connected, through a relatively high resistance 29, to the other wire 25, while terminal 23 is connected, to a relatively low resistance 31, to the same wire 25. The resistances 29 and 31 are considered as embodied in a single heating unit. When the knob is suitably actuated and is in any position on the scale 13, since terminals 19, 21, and 23 are all connected together, resistances 29 and 31 will be connected in parallel across the power wires 25 and 27. The current will therefore be relatively high, and the heating effect will accordingly be great. However, on expiration of the pre-set time interval, connection will be broken between terminals 21 and 23, and hence resistance 31 will drop out of circuit and only resistance 29 will be connected across the wires 25 and 27. Since resistance 29 is relatively high, the current flow will be considerably less, and the heating effect will accordingly be diminished. This condition takes place when the knob 3 has reached the "low" index position 11. Low heat will continue as long as the switch is allowed to remain untouched, but when the knob 3 is manually turned from "low" position 11 to "off" position 9, connections are additionally broken between the terminals 19 and 21, and therefore neither of the resistances 29 or 31 will receive current and the heating means will accordingly be disconnected entirely.

The arrangement described is of considerable utility in connection with cooking, for example, where it is desired to cook a food for a certain length of time at a relatively high temperature, after which a long slow simmering period at lower heat is needed. Or, the "low heat" period may be considered as merely a warming period during which the food, properly cooked during the "high heat" period, is kept warm for serving purposes.

The general character and utility of the switch having thus been described, its construction will now be gone into in greater detail.

Broadly speaking, the time-controlled switch comprises two parts, namely, the mechanical switching mechanism and the time delay mechanism, which are interconnected by a series of latches and the like. For clarity, the mechanical switching mechanism will first be described, and thereafter the time delay mechanism, while the two will be correlated in connection with the description of the operation of the switch as a whole.

The mechanical switching mechanism is mounted entirely upon the base 17. It comprises a pair of terminals 33 and 35 (see Fig. 3), which are supported on projections 37 and 39, respectively, molded integrally with the base 17. Each terminal comprises a flat piece of brass having

a portion 41 which fits into a companion receiving depression in the projections 37 and 39, and an outwardly extending, knife-edged portion 43. Terminal piece 35 also has a sidewardly extending brass plate 45 mounted concentrically therewith, the end of the piece 45 serving as a fixed contact for one of the switching devices. Numeral 47 indicates a third terminal piece that is likewise mounted on the base 17. The terminal piece 47 supports a curved spring 49, the edge of which appears in Fig. 3. On the free end of the spring 49 is mounted a camming plate 51. The tendency of the spring 49 is normally to engage the end face of the contact plate 45, to make electrical connection between the terminals 35 and 47, but when a suitable camming device is brought to bear against the plate 51, the end of spring 49 is lifted away from the end of plate 45, thereby to break connections.

The terminals 33, 35, and 47 are each mounted on the base 17 in the manner illustrated in Fig. 4 for terminals 33 and 35. An inwardly threaded hollow cylinder 53 is molded permanently into the base 17, and extends therethrough. The inner end of the cylinder 53 is upset as at numeral 55 to clamp the respective portions 41 of the terminals. Into the outer end of the cylinders 53 are threaded the binding post screws 19, 21, and 23, which screws comprise the means for making exterior connections to the switch.

Mounted on a pin 57 which is supported in the base 17 (see Figures 3 and 4) is a rotating contactor bar assembly. This assembly comprises a spacing washer 59, a double-blade contactor bar per se 61, a second spacing washer 63, and an anvil piece 65. The contactor bar 61 has two arms 67 and 69, which extend radially from the pin 57 in such directions that when one engages the terminal 33, the other will be engaging the terminal 35. The arms of the bar 61 each comprise two spaced blades of spring material, such as copper, brass or bronze, and each blade terminates sidewardly with flared lips 71, so as the better to engage the terminals 33 and 35. The anvil piece 65 preferably comprises fiber or similar material, and includes, on its upper surface, a substantially rectangular notch 73. A projection 75 from contactor bar 61 fits into a hole 77 in the anvil piece 65, whereby rotation of the anvil piece 65 relatively to the contactor bar 61 is positively prevented.

It will readily be seen that through rotation of the anvil piece 65, the terminals 33 and 35 may be connected or disconnected at will with the coextensive rotation of the contactor bar 61. The devices thus far described may be characterized as the electrical elements of the mechanical switching mechanism.

The switch operating mechanism is in part mounted upon a pin 79 which is supported in base 17 (see Figures 3 and 8). Mounted on the pin 79 is a swingable hammer saddle member 81, which comprises an arm 83, at the upper end of which is a hole through which the pin 79 passes, a cross piece 85, and a portion 87 parallel to the arm 83. On the cross piece 85 is a nose 89, the function of which will be indicated hereinafter. The arm 83 is of suitable length such that the cross piece 85 at all times fits within the notch 73 in the anvil piece 65. Swinging of the hammer saddle 81 is limited by a pair of projections 91 molded on the base 17.

Mounted on a second pin 93, supported in base 17 in a manner parallel to but spaced from pin 79, is a member 95, which comprises a plate 97

which is parallel to the axis of the pins 19 and 93, but displaced therefrom, and a pair of projections 99 extending at right angles from the plate 97 and drilled to slide on the pin 93. The plate 97 is drilled to receive one end of a tension spring 101, the other end of which is anchored to a pin 103 mounted near the edge of base 17. The forward end of plate 97 is bent, as indicated at numeral 105, so that it seats against pin 19 under the action of spring 101. The bent portion 105 is terminated by a nose 107, which receives one end of a compression spring 109, the other end of which engages the nose 89 on cross piece 85 of hammer saddle member 81. The upper projection 99 has an oppositely extending portion 111, the end of which is provided with an upturned ear 113 for purposes to be described.

The compression spring 109, member 95, and hammer saddle 81 together constitute an over-centering device, as follows: When the member 95 is rotated counterclockwise, against the spring 101, and the hammer saddle 81 is held stationary by reason of its engagement with the upper (Fig. 3) projection 91 (in other words, when the member 95 is rotated counterclockwise from its position as indicated in Fig. 3), the compression spring 109 is slowly compressed against the nose 89 on the hammer saddle 81, until a point is reached where the nose 89, the axis of the spring 109, and the nose 107 are all in line and radial to the pin 93. As the member 95 passes this position, the force of the compression spring is liberated by its swinging the hammer saddle sharply downward, in a clockwise manner, until it is stopped by the lower projection 91. The reverse action takes place when the member 95 is returned to its original position, as it rotates clockwise under the force of spring 101, and the hammer saddle is swung sharply upward in a counterclockwise manner. As the hammer saddle 40 swings, its cross piece 85 is forced sharply against opposite sides of the notch 73 in the anvil piece 65, thus snapping the contactor bar 67 into and out of connection with the terminals 33 and 35. In this manner contacts are made and broken 45 with a much-to-be-desired snap action, and thus arcing and sparking, and consequent pitting and erosion of the contacts is avoided.

This substantially completes the description of the mechanical switching mechanism, and the time delay mechanism will next be described.

The time delay mechanism, broadly, comprises a main spring, an escapement train permitting said main spring to unwind itself only in a slow, controlled manner, and a latch device which cooperates with the mechanical switching device to operate the same. The time delay mechanism is mounted between two brass plates 115 and 117 (see Figures 4 and 9), which are spaced apart by collars 119 on screws 121. The plate 115 is in turn mounted on pillars 123 projecting from base 17, by means of screws 125 that extend through to the exterior of the base 17. The plate 115 desirably is provided with holes for receiving the upper ends of pins 19 and 93, to aid in supporting said pins.

The time delay mechanism as a whole operates upon the main shaft 5, which, it will be remembered, extends from the front of the switch housing. Said shaft 5 is borne in the plates 115 and 117, and has mounted thereon, immediately beneath the plate 117, a coiled main spring 127, the inner end of which is securely affixed to said shaft. The outer end of the main spring 127 is secured to a projection 129 struck from the

relatively immovable plate 117. Similar projections 129 are provided at spaced intervals around the main spring 127, serving to hold it in position. The inner edge of main spring 127 is protected by a cover plate 131, which is secured 5 to the shaft 5, and is rotatable therewith.

Immediately behind the cover plate 131 a collar 133 is mounted on the main shaft 5, the collar 133 serving to space a main gear 135. The gear 135 rotates freely on and relative to the main 10 shaft 5. Immediately behind the main gear 135 is a spring disc member 137, which comprises a central portion which is secured to the shaft 5 against rotation relative thereto, and a dished or flanged periphery 139 which is sprung to bear 15 forcibly upon the surface of main gear 135. The frictional force of the periphery 139 on the gear 135 is such that, when the main shaft 5 is manually rotated, as in setting the switch, the disc 137 slips freely on the surface of the gear, without carrying it in coextensive rotation, but when the main spring alone is tending to unwind, through the escapement train, the slow force is sufficient that the gear 135 is compelled to rotate simultaneously with the main shaft 5. This arrangement constitutes a form of clutch, in which engagement is had provided the force is applied to the driven member in a very slow, uniform manner, but in which no engagement is had if the force is applied quickly and unevenly (as it is 30 with manual rotation of the main shaft 5).

Behind the disc 137 on the shaft 5 is mounted a small disc 141, which has a projection 143 in its own plane. The disc 141 is immovable relative to the shaft 5. Its function will be indicated 35 hereinafter.

Engaging the main gear 135 is a pinion 145, which constitutes the first element of a timing or escapement train. The escapement train will not be described in great detail herein, since it 40 may be of the same general type as those shown in my Patents Numbers 1,895,398 and 1,895,399, dated January 24, 1933. Broadly, it comprises a series of pinions 145 and gears 147, which are arranged one gear and one pinion to a shaft, 45 each shaft being supported in bearings in the plates 115 and 117, and which together effect a large increase (or decrease) in angular rotation from the main shaft 5 to an escapement mechanism 149. The escapement 149 comprises 50 a toothed wheel 151 and a balance wheel 153, the latter being mounted on a balance staff 155 having a notch 157 therein which, together with a pin 159 mounted on the balance wheel 153 allows the escapement wheel 151 to rotate only one 55 tooth at a time, and at definite intervals. For a further description of the escapement mechanism, reference is made to my Patent No. 1,995,363, dated March 26, 1935.

It will now be seen that the operation of the 60 timing means is substantially as follows: Assume that the device is initially "run down" and at rest. The shaft 5 is manually rotated in a direction to wind the main spring 127 (this direction being counterclockwise in Fig. 9). As 65 the main spring is wound, the clutching mechanism 137 slips and the main gear 135 remains stationary. However, whenever the winding is stopped, the clutching means 137 immediately takes hold of the gear 135, and further rotation 70 of the shaft 5 and gear 135 is simultaneous. As soon as the winding is stopped, there is placed upon the shaft 5 a clockwise torque, by reason of the tendency of the main spring 127 to unwind itself. The shaft 5, however, cannot now rotate 75

without rotating the main gear 135, and the main gear 135 can rotate only in a very slow, timed manner as controlled by the escapement mechanism and gear train. Thus, the main shaft 5, after once having been wound, can unwind under its own power only at a predetermined, slow speed. If the shaft 5 is rotated manually in a clockwise (unwinding) direction, however, the clutch 137 again slips and the main spring may be manually returned to "run down" position without awaiting the action of the escapement mechanism.

Supported on a pivot screw 161 (Fig. 9) which is mounted on the under side of plate 115 is a latch lever 163, the particular construction of which is indicated in Fig. 10. Referring to Fig. 10, it will be seen that the lever 163 comprises a stamping of relatively thin sheet metal or the like which has the general shape of an approximately squared C. A hole 165 at one corner provides for the pivot screw 161. At the same corner, a projection 167 is bent upwardly from the lever 163, and in assembly this projection 167 receives one end of a tension spring 169 (see Fig. 9), the other end of which is hooked around a post 119 mounted on the upper side of plate 115. Projection 167, it will be understood, extends across the edge of plate 115. Spring 169 tends at all times to rotate lever 163 on pivot 161 in a counterclockwise (Fig. 9) manner. Returning to Fig. 10, the short end of the lever 163, considered from pivot 161, is provided with a camming nose 173 which in operation engages the camming plate 51 on movable contact spring 49 (see Figures 3, 5, 6, and 7). Near its other corner, the lever 163 is provided with a stamped projection 175, an end 177 on which is positioned, in assembly, to interrupt the swinging motion of hammer saddle 81 of the mechanical switching assembly. The far end of lever 163 includes an upwardly-turned projection 179, which passes, in assembly, through a suitable arcuate slot 181 in plate 115 (see Fig. 9) in position to engage (or disengage) projection 143 on disc 141 on shaft 5. Numeral 183 (Fig. 9) indicates a dog that is pivoted on the upper or inner surface of plate 115 on a pivot screw 185 mounted in said plate 115. The dog 183 has a projection 187 extending in one direction to be in position to intercept the movement of projection 143 on disc 141 on main shaft 5, while in the other direction it extends out over the edge of plate 115 and is provided with a downwardly-turned ear 189 which is positioned to engage and disengage ear 113 on portion 111 of member 95 of the mechanical switching mechanism. A tension spring 191 reacts between projection 189 and one of the screws 119, and tends at all times to turn dog 183 in a clockwise (Fig. 9) direction.

The above completes the description of the various elements of the mechanical switching device and the time delay mechanism. The joint operation of the two will now be described.

Assume, again, that the device is initially in "run down" position, the main spring being unwound. The mechanical switching elements are in their position as indicated in Fig. 3, all connections being off. The main shaft 5 is now manually rotated, as by turning knob 3, in a direction adapted to wind the main spring. During the first few degrees of rotation, projection 143 on disc 141 moves from its solid-line, Fig. 9 position, to its dotted-line position, and in so doing permits projection 179 on lever 163 to follow it under the action of spring 169, likewise moving

from its solid-line position to its dotted line position. This means that nose 173 of lever 163, which heretofore has been bearing on camming plate 51 of spring contact arm 49, as shown in Fig. 3, will be lifted therefrom, permitting said spring contact arm 49 to abut the fixed contact plates 45, as shown, for example, in Fig. 7, thereby to complete the circuit between exterior terminals 19 and 21. By the time the projection 143 has reached its dotted-line, Fig. 9 position, the knob 3 will be located at the "low" index position 11, Fig. 1. Further rotation of the main shaft 5, will cause the projection 143 on disc 141 to abut the projection 187 on dog 183, and rotate said dog in a clockwise (Fig. 9) manner on its pivot 185. In so moving, projection 189 of dog 183 is brought to bear forcibly against projection 113 of member 95, and said member 95 is caused to rotate on its pivot pin 93 in a counterclockwise (Fig. 3) direction. As heretofore described in connection with the operation of the mechanical switching device, this rotation of the member 95 will cause a snapping rotation of the hammer saddle 81, with the result that the anvil piece 65 is rotated on its pivot 57, and the contactor bar assembly is rotated to the Fig. 5 position, where exterior terminals 21 and 23 are now connected together.

In moving to its Fig. 5 position, the hammer saddle 81 will have ridden over the projection 177 on lever 163, and lodged therebehind, as shown in Fig. 5. Until this projection 177 is removed, therefore, the hammer saddle 81 is not permitted to swing in a reverse manner.

As the knob 3 is rotated still further, projection 189 passes out of engagement with projection 113, and since the engagement of these projections was the only force urging the member 95 to rotate in a counterclockwise direction, against its own spring 101, the moment this engagement stops the spring 101 will act to return the member 95 to its original position. This it proceeds to do, and the member 95 assumes the position shown in Fig. 6. However, with this return movement of the member 95, the hammer saddle 81 cannot cooperate, because of its engagement with the projection 177 of latch lever 163. The return movement of the member 95, however, cocks the compression spring 109 into position to snap the hammer saddle back to its original position as soon as the projection 177 is removed; in other words, the Fig. 6 position, which by this time has been assumed, is one in which the hammer saddle 81 is cocked to throw the anvil piece 65 in a clockwise rotation as soon as the latch projection 177 is removed, thereby to break connection between exterior terminals 21 and 23.

By this time, the knob 3 in its rotation will have passed the dot or other suitable index mark 15, as shown in Fig. 1. Instructions to the user of the switch should specify that, for any controlled operation, the handle 3 should first be rotated past the dot 15. Thereafter, the knob 3 may be set to any desired location on the scale 13, for any desired time interval, be it greater or lesser than the time interval represented by the position of the dot 15 relative to the scale 13.

In the Fig. 6 position of the elements, both switches are now "on". While all of the foregoing has been going on, the main spring has been wound, but the clutch 137 has been slipping to prevent rotation of the main gear 135 of the timing train. The time delay to be set, it will

be seen, is proportional to the rotation of the main shaft 5 in the winding direction.

Assuming that the requisite delay has been set, the rotation of the knob 3 and main shaft 5 is stopped, the escapement means immediately comes into operation in the manner specified, allowing the main shaft to return or to "run down" only at a measured, slow speed. Nothing happens until the knob 3 nears the "low" index position 11, when the projection 143 of disc 141 engages the reverse face of projection 181 of dog 183. In this direction of movement, however, projection 143 is able to force dog 183 aside, against the action of spring 191, since there is no obstruction present to the counterclockwise (Fig. 9) rotation of the dog 183. Finally, the projection 143 passes the dog 183, and again assumes its dotted-line (Fig. 9) position. Continuing the movement, the projection 143 now begins to bear against the projection 179 of latch lever 163, causing said lever to rotate on its pivot 161 against its spring 169. The first thing that happens is that the latch lever 163 is rotated sufficiently far so that the projection 177 is removed from its effective holding position against the hammer saddle 81. Thereupon, instantaneously, the cocked compression spring 109 swings the hammer saddle 81 back to its original or rest position, as shown in Fig. 7, thereby disconnecting the contact bar assembly from the terminal pieces 33 and 35 and opening the circuit between the exterior terminals 21 and 23. The opening of the circuit between the terminals 21 and 23 is thus performed in an automatic, timed fashion. The exterior terminals 19 and 21, however, are still connected together by the movable spring contact 49. At this stage of operation, represented in its entirety by Fig. 7, the knob 3 will have reached the "low" index position 11 on the face 40 of the switch, as indicated in Fig. 1.

The timing train and escapement mechanism now stalls, because its power is not sufficient to move the latch lever 163 against the reaction of spring contact arm 49. If, however, the knob 3 is manually grasped and rotated back to "off" index position 9, this remaining motion of the main shaft 5, in order to bring the projection 143 of disc 141 to its full-line, Fig. 9 position, is manually brought about, and in so doing the latch lever 163 is further rotated an amount sufficient to force the nose 173 thereof to bend spring contact arm 49 away from fixed contact 45, thus breaking the connection between said spring contact arm 49 and the fixed contact 45, and therefore breaking connection between the exterior terminals 19 and 21.

When the knob 3 is thus returned to its "off" index position 9, all of the elements will again have resumed their full line, Fig. 9 position, and the positions indicated in Fig. 3, and the device will be ready for a subsequent manipulation.

It will readily be seen that at any time while the time delay is running (in other words, at any time after the device has reached the position indicated in Fig. 6), the knob 3 may be manually grasped and returned to "low" index position 11, with the result that exterior connections between terminals 21 and 23 are broken. This sometimes happens in the event that it is suddenly desired to discontinue the high heating period. Similarly, the additional manual operation required to disconnect exterior terminals 19 and 21 (return of the knob 3 of "off" index position 9) may be accomplished at any time.

In view of the above, it will be seen that the

several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. A time-controlled switch comprising a manually rotatable main shaft, a pair of electric switches each having open circuit and closed circuit positions, means connected to said main shaft operable on rotation of said main shaft through a given angle to move one of said switches from one to another position, and additional means operable upon rotation of said main shaft through a given greater angle to move the second switch from one to another position, and upon rotation through still a greater given angle to urge said second switch back to its first position, a latching mechanism operated by the rotation of said main shaft and interposable in the path of said additional means thereby to prevent, temporarily, said second switch from being returned to its first position, and a timing train operative after a predetermined time interval to remove said latching mechanism from the path of said additional means to permit said second switch to return to its first position.

2. A time-controlled switch comprising a manually rotatable main shaft, a pair of electric switches each having open circuit and closed circuit positions, means connected to said main shaft operable on rotation of said main shaft through a given angle to move one of said switches from one to another position, and additional means operable upon rotation of said main shaft through a given greater angle to move the second switch from one to another position, and upon rotation through still a greater given angle to urge said second switch back to its first position, a latching mechanism operated by the rotation of said main shaft and interposable in the path of said additional means thereby to prevent, temporarily, said second switch from being returned to its first position, and a timing train operative after a predetermined time interval to remove said latching mechanism from the path of said additional means to permit said second switch to return to its first position.

3. A time-controlled switch comprising a manually rotatable main shaft, a pair of electric switches each having open circuit and closed circuit positions, means connected to said main shaft operable on rotation of said main shaft through a given angle to move one of said switches from one to another position, and additional means operable upon rotation of said main shaft through a given greater angle to move the second switch from one to another position, and upon rotation through still a greater given angle to urge said second switch back to its first position, a latching mechanism operated by the rotation of said main shaft and interposable in the path of said additional means thereby to prevent, temporarily, said second switch from being returned to its first position, and a timing train operative after a predetermined time interval to remove said latching mechanism from the path of said additional means to permit said second

- switch to return to its first position, said timing train including a main spring which is likewise connected to said main shaft to be tensioned by the rotation thereof, the time interval during which said latching means is operable being directly proportional to the angle through which said main shaft is rotated.
4. A time-controlled switch comprising a manually rotatable main shaft, a pair of electric switches each having open circuit and closed circuit positions, means connected to said main shaft operable on rotation of said main shaft through a given angle to move one of said switches from one to another position, and additional means operable upon rotation of said main shaft through a given greater angle to move the second switch from one to another position, and upon rotation through still a greater given angle to urge said second switch back to its first position, a latching mechanism operated by the rotation of said main shaft and interposable in the path of said additional means thereby to prevent, temporarily, said second switch from being returned to its first position, and a timing train operative after a predetermined time interval to remove said latching mechanism from the path of said additional means to permit said second switch to return to its first position, said first-named means comprising a cam.
5. A time-controlled switch comprising a manually rotatable main shaft, a pair of electric switches each having open circuit and closed circuit positions, means connected to said main shaft operable on rotation of said main shaft through a given angle to move one of said switches from one to another position, and additional means operable upon rotation of said main shaft through a given greater angle to move the second switch from one to another position, and upon rotation through still a greater given angle to urge said second switch back to its first position, a latching mechanism operated by the rotation of said main shaft and interposable in the path of said additional means thereby to prevent, temporarily, said second switch from being returned to its first position, and a timing train operative after a predetermined time interval to remove said latching mechanism from the path of said additional means to permit said second switch to return to its first position, said switches having a common terminal.
6. A time-controlled switch comprising a manually rotatable main shaft, a pair of electric switches each having open circuit and closed circuit positions, means connected to said main shaft operable on rotation of said main shaft through a given angle to move one of said switches from one to another position, and additional means operable upon rotation of said main shaft through a given greater angle to move the second switch from one to another position, and upon rotation through still a greater given angle to urge said second switch back to its first position, a latching mechanism operated by the rotation of said main shaft and interposable in the path of said additional means thereby to prevent, temporarily, said second switch from being returned to its first position, and a timing train operative after a predetermined time interval to remove said latching mechanism from the path of said additional means to permit said second switch to return to its first position, said first-named switch including spring means of sufficient strength that it is impossible for said main shaft to be rotated against said spring means only under the action of said timing train.
